DESIGN FOR A SCALE

Harold L. van Doren and John G. Rideout,
Toledo, Ohio

Application May 10, 1935, Serial No. 56,776

Term of patent 14 years

To all whom it may concern:

Be it known that we, Harold L. van Doren and John G. Rideout, citizens of the United States, residing at Toledo, in the county of Lucas and State of Ohio, have invented a new, original, and ornamental Design for a Scale, of which the following is a specification, reference being had to the accompanying drawings, forming a part thereof.

Figure I is a perspective view presenting substantially the customer's side of a scale showing our new design; and

Figure II is a perspective view presenting substantially the merchant's side thereof.

We claim:

The ornamental design for a scale as shown.

HAROLD L. VAN DOREN.

JOHN G. RIDEOUT.
